ADDRESS STAMPING DEVICE

Edwin Szydlek, Detroit, Mich.

Application August 15, 1956, Serial No. 42,621

Term of patent 14 years

(Cl. D64—10)

Fig. 1 is a front elevational view of an address stamping device showing my new design;

Fig. 2 is a top plan view thereof;

Fig. 3 is a side view looking from the right of Fig. 1; and

Fig. 4 is a side view looking from the left of Fig. 1.

The rear view, not shown, is substantially symmetrical to the front elevational view.

The essential features of my design reside in the portions shown in solid lines in the drawing.

I claim:

The ornamental design for an address stamping device, substantially as shown and described.
